Primary Examiner — Vy N Koenig*Assistant Examiner* — Elizabeth Anne Glassberg(74) *Attorney, Agent, or Firm* — Chun-Ming Shih; LANWAY IPR SERVICES(57) **CLAIM**

The ornamental design for a leash for animals as shown and described.

DESCRIPTION

FIG. 1 is a perspective view of a leash for animals showing the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures illustrate portions of the leash for animals that form no part of the claimed design.
